UNITED STATES PATENT OFFICE.

JOHN PETER OWSIANEK, OF ITUNA, SASKATCHEWAN, CANADA.

AUTOMOBILE JACK.

Application filed April 26, 1922. Serial No. 556,803.

To all whom it may concern:

Be it known that I, JOHN PETER OWSIANEK, a subject of the King of Great Britain, and resident of Ituna, in the 5 Province of Saskatchewan, in the Dominion of Canada, have invented certain new and useful Improvements in Automobile Jacks, of which the following is a specification.

This invention relates to automobile jacks, 10 and has for its objects to provide a lifting jack that is designed to be operated through suitable lever arrangement by a rack and gear mechanism, to provide a lifting jack, which is designed to be raised and subsequently lowered by the same movement of 15 the lever.

Further objects are to provide a means of controlling the line of axis of the gears in order to force the gears in and out of mesh 20 with the rack at will.

Further objects are to provide in combination with a lifting jack, a combination pulley or handle which is to be used to operate the jack and which consists of a shank 25 or handle bar which is provided at one end with a recess designed to engage the operating lever, and on which are formed wrenches, a hammer head, a screw driver, etc.

30 Further objects are to provide a means whereby the lifting jack may be used as a hauling device, to provide a suitable means whereby the jack may be anchored to the ground when used as a hauling device, to provide pulleys in the jack body which have 35 a knurled engaging surface between which a cable is to be engaged.

Still further objects are to provide a combination lifting jack, that is simple in construction, not liable to go out of repair, and generally to adapt the several parts to better perform the functions required of it.

With the above and other objects in view, the invention consists essentially of the improved construction, hereinafter described 45 in detail in the accompanying specification and drawings.

In the drawings:—

Figure 1 is a vertical section taken 50 through the lifting jack and showing the gears set for the raising operation.

Figure 2 is a vertical section through the improved jack showing both the gears in engagement with the rack and locking the 55 same in position.

Figure 3 is a vertical section through the improved jack showing the gears set for the lowering operation.

Figure 4 is a longitudinal section taken 60 on the line 4—4 of Figure 3.

Figure 5 is a detail showing in elevation the gears and operating lever mechanism.

Figure 6 is a sectional detail taken through one of the dogs.

Figure 7 is a cross section on the line 7—7 65 of Figure 6.

Figure 8 is a cross section on the line 8—8 of Figure 6.

Figure 9 is a perspective view of one of 70 the dogs.

Figure 10 is a side view partly in section and partly in elevation of the improved combination operating handle.

Figure 11 is a plan view of the same.

Figure 12 is a fragmentary plan view of 75 the operating handle in extended position.

Figure 13 is an enlarged sectional detail of the clamping connection shown in Figure 12.

Figure 14 is a side elevation of the jack 80 used as a hauling device.

Figure 15 is a detail plan view of the toothed rack.

Figure 16 is a bottom plan view of the 85 foot used on the lifting jack.

Like characters of reference indicate corresponding parts in all the figures.

Referring to the drawings, A represents the improved jack comprising an elongated hollow body 10, which is formed adjacent 90 its upper end with a lateral hollow extension 11. Slidably mounted within the hollow body 10 is a toothed rack 12 formed at its upper end with a saddle 13 on which the tire or axle or other part of the machine 95 to be raised is placed.

Mounted in the hollow extension 11 is a plate 14 pivotally carried on an axle 15, which is retained by means of nuts 16. The plate 14 is connected by two cross-wise 100 spindles 17 and 18 to a triangular plate 19 formed integral at one end of a lever 20.

The lever 20 is provided with a pin 21, which is designed to engage one of three recesses 22, 23 and 24, which are provided in 105 one of the walls of the lateral extension 11. It is obvious that through this means, when the lever 20 is pivoted on its fulcrum 15, it may be located in three different positions corresponding to the recesses 22, 23 and 24. 110

Mounted on the spindles 17 and 18 are two gears 25 and 26 designed to mesh with the toothed rack 12 and its axial position is controlled by the operation of the lever 20.

5 An arm 27 is provided, which is formed with an eye 28, encircling the spindle 17, while a similar arm 29 is formed with a like eye 29^a, which engages the spindle 18. The arms 27 and 29 extend outwardly of the extension 11 and have their outer ends connected by a link 30. The link 30 is pivotally connected to the outer ends of the arms 27 and 29 and is provided intermediate of its length with a bolt or threaded pin 31, which is designed to extend through an elongated slot 32 formed in a lever 33, which is fulcrumed at 34 to the walls of the lateral extension 11.

10 The arms 27 and 29 are both provided with a spring actuated dog 35, but as these two dog arrangements are exactly similar in both cases, one of them only will be described here, but it is to be understood that the two arms 27 and 29 are to be provided 15 with a similar spring actuated dog.

15 The dog 35 is formed with a longitudinal slot 36 through which extends a bolt 37, which bolt engages a sleeve or covering member 38, and has its threaded end extending through the arm 27 and securely retained therein by means of a nut 39.

20 The sleeve 38 may be suitably provided by means of a metal covering which has flanges 40 connected to the arm 27 by any suitable fastening medium.

25 The sleeve or cover 38 is formed adjacent its lower end with a slot 41 through which extends the shank of the screw nail 42 which is in threaded engagement with the body of the dog 35.

30 Obviously this screw nail 42 extending through the slot 41 of the sleeve and the bolt 37 extending through the slot 36 of the dog provides a means whereby the dog is slidably retained within the sleeve along the arm 27.

35 The dogs 35 may be provided at their upper ends with a bored head 43 through which they may be connected by suitable links designed to reinforce the link 30 joining the arms 27 and 29.

40 The pin 31 on the link 30 which extends through the slot 32 in the lever 33 is loosely maintained in engagement in the slot 32 by means of a nut 44, which is in threaded engagement with the threaded end of the pin or bolt 31.

45 The lower end of each of the dogs 35 is provided with toothed projections 45 and 46, which are designed to engage two of the teeth of the gears 25 and 26, so that the jack may be raised uniformly although the lever 33 is brought back and forth.

50 When the rack 12 is to be raised and the lever 20 is grasped and pulled out in the

position corresponding to the recess 24 in the wall of the lateral extension 11, which recess will be engaged by the pin 21 on the lever, thus locking the lever in position and the position thus assumed, the lever will withdraw the lower gear 26 from the teeth of the rack 12 and will force the upper gear 25 into mesh with the teeth of the rack as shown in Figure 1 of the drawings.

55 The lever 33 is then actuated back and forth in its downward movement, and it will force the tooth 46 of one of the dogs 35 to engage one of the teeth of the upper gear 25, which will move the same to the left, and force the rack 12 upwardly, when 60 the lever 33 is then raised, the second dog 35 will work on the lower gear 26, and cause the same to rotate to the left. The gear 26 will transmit its motion in a reverse direction to the gear 25 which will thus actuate the rack 12 in the same motion, thus affording on the two movements of the lever 33 a uniform raising motion. When the rack has reached the height desired, the lever 20 is brought to neutral position, that is the 65 pin 21 is brought into engagement with the recess 23 provided in the wall of the lateral extension 11, when the two gears 25 and 26 will be in mesh with the rack 12 as shown in Figure 2 of the drawings, thus locking 70 the rack in position.

75 When the rack is to be lowered, the lever 20 is again moved towards the body 10 of the lifting jack and the pin 21 brought into engagement with the recess 22, thus withdrawing the gear 25 from engagement with the rack and forcing the gear 26 to mesh with the teeth of the rack 12. The lever 33 is then actuated back and forth as previously, and the action is reversed as the 80 gear 26 is then the one which transmits the motion to the rack 12.

85 It will be obvious that the rack will be lowered by the movement of the gear 26, which is propelled by the dogs 35. In order to afford a better means of operating the lever 33, the same is formed with an arrow extension 47, which is designed to engage a recess 48 formed in the end of a handle bar 49, which is provided with an extension 50. The extension 50 carries a collar 60, which engages the bar 49 and the outer end of the bar 49 carries a similar collar 61, which is provided with a set screw 62 designed to be tightened on the extension 50, and securely lock the same in its extended or collapsed position.

90 The member 49 may be formed as a combination tool being provided on one side with a hammer head 63, while opposite to this wrenches 64 and 65 are provided. If desired also the outer end of the extension 60 may be formed with a screw driver 66, which may also be provided with an orifice 67, of such shape as to be designed to en- 95

gage the standard nuts to be used on the lifting jack.

The collars 60 and 61 on the extension and on the handle bar 49 may be suitably secured 5 thereto by means of rivets as shown at 68 and 69.

The rack 12 is to be slidably retained within the hollow body 10 by means of a pin 70 extending crosswise at the lower end 10 of the rack 12 and designed to become engaged by recesses 71 formed in the lateral walls of the body 10 of the lifting jack.

This lifting jack may be operated by the movement of the lever 33, which is provided 15 with the combination member 49 according to the method already described, and the rack 12 will be limited in its upward movement by the pin 70 being brought into engagement with the recess 71 formed in the 20 inner walls of the body 10.

The jack A may also be adapted to be used as a hauling device, according to the following.

The hollow member 10 is mounted on a 25 foot 72, which is wedge shaped at one end 73, and has its other end notched as at 74 in order to allow the free passage of a cable 75, which is to be engaged between two pulleys 76 and 77 mounted on the spindles 30 17 and 18 respectively adjacent the gears 25 and 26.

The gripping surface of the pulleys 76 and 77 is knurled in order to firmly engage 35 the cable 75, the outer end of which extends underneath the pulley 76 between the two lateral walls of the extension 11 at the upper end thereof.

When the jack is to be used for hauling 40 purposes, the rack 12 is extended completely outwardly, until the pin 70 comes into engagement with the recess 71 and the jack being placed flat on the ground, the wedge 73 is driven into the same. For this purpose 45 the rack may be formed at its upper end with a slot 78 in which rollers 79 are mounted, which frictionally engage a spike 80 which may be driven into the ground by means of the hammer provided on the member 49. Also in order to provide a further 50 means of securing the jack to the ground, a plate formed with inclined spikes 81 is provided, which may be suitably strapped to the rack 12.

When the device is to be used for this purpose, as for instance when the car is caught 55 in a mudhole, and cannot make any more progress, the device is set in front of the car as previously described and shown in Figure 14 of the drawings, and the cable being engaged between the pulleys 76 and 77, one end of the cable is rolled on the front axle of the car, and the lever 33 being actuated through the member 49, the pulleys 76 and 77 will be rotated inwardly, and thus 60 pull the cable 75, which it firmly engages, 65

the gear will thus readily be pulled out and the device is dismounted, and when placed in collapsed position does not occupy a larger space than an ordinary lifting jack.

Obviously through this, an improved 70 combination device has been provided which affords an efficient lifting jack, and a hauling device that may be suitably operated when the same is needed in a place where it would be difficult to get help otherwise. 75

As many changes could be made in the above construction, and many apparently widely different embodiments of my invention, within the scope of the claims, constructed without departing from the spirit 80 or scope thereof, it is intended that all matter contained in the accompanying specification and drawings shall be interpreted as illustrative and not in a limiting sense. 85

What I claim as my invention is:

1. A lifting jack of the class described, comprising a hollow elongated body formed with a lateral hollow extension adjacent its upper end, a toothed rack slidably mounted within the hollow body, gears mounted in the extension, a lever designed to operate the gears, and means to control the position of the gears to raise, lower or lock the rack. 90

2. A lifting jack of the class described, comprising a hollow elongated body formed with a lateral hollow extension, adjacent its upper end, a toothed rack slidably mounted within the hollow body, gears mounted in the extension, an arm on each gear, a link pivotally joining the two arms, dogs on each end of the link engaging the gears, a lever operatively connected to the link, and means to control the position of the gears to raise, lower or lock the rack. 95

3. A lifting jack of the class described, comprising a hollow elongated body formed with a lateral hollow extension adjacent its upper end, a toothed rack slidably mounted within the hollow body, gears mounted within the extension, an arm on each gear, a link pivotally joining the two arms, dogs on each end of the link engaging the gears, resilient means coiled around the dogs, sleeves housing the dogs, and resilient means controlling the movement of the dogs, means to slidably retain the dogs within the sleeve, a lever operatively connected to the link, and means to control the position of the gears to raise, lower or lock the rack. 105

4. A lifting jack of the class described, comprising a hollow elongated body formed with a lateral hollow extension, adjacent its upper end, a toothed rack slidably mounted within the hollow body, a lever formed integral with a notched portion pivotally mounted within the extension, gears mounted on the notched portion, means to operate the gears, and means to lock the lever in three positions, as and for the purpose described. 110

5. A lifting jack of the class described, 115

and in combination, a hollow elongated body formed with a lateral hollow extension adjacent its upper end, a toothed rack slidably mounted within the hollow body, gears 5 mounted within the extension, means to control the position of the gears, a lever designed to operate the gears, a handle bar formed at one end with a recess designed to engage the lever, and a longitudinally 10 sliding extension on the handle bar.

6. A lifting jack of the class described, and in combination, a hollow elongated body formed with a lateral hollow extension adjacent its upper end, a toothed rack slidably 15 mounted within the hollow body, gears mounted in the extension, means to control the position of the gears, a lever designed to operate the gears, a handle bar formed at one end with a recess to engage the lever, 20 a hammer head on the handle adjacent the recess end, and a longitudinally sliding extension on the handle bar.

7. A lifting jack of the class described, comprising a hollow elongated body formed 25 with a lateral hollow extension adjacent its upper end, a toothed rack slidably mounted within the hollow body, means to slidably retain the rack within the hollow body, gears mounted within the extension, a lever 30 designed to operate the gears, and means to control the position of the gears to raise, lower or lock the rack.

8. A lifting jack of the class described

and in combination, a hollow elongated body formed with a lateral hollow extension adjacent its upper end, a wedge shaped foot on the body, a toothed rack slidably mounted within the hollow body, adjustable plates in the extension provided with spindles, gears on the spindles, pulleys on the spindles adjacent the gears, means to operate the gears, and means to change the plane of axis of the gears, as and for the purpose described. 35

9. A lifting jack of the class described, and in combination, a hollow elongated body, formed with a lateral extension adjacent its upper end, a wedge shaped foot on the body designed to be driven into the ground, a toothed rack in the body provided with a slot through which a spike may be driven into the ground, adjustable plates in the extension provided with spindles, gears on the spindles, pulleys having a knurled surface on the spindles, a cable extending within the hollow extension and engaged by 40 the two pulleys, means to operate the gears, and means to control the line of axis of the gears and pulleys, as and for the purpose 45 described. 50

In witness whereof I have hereunto set 55 my hand in the presence of two witnesses.

JOHN PETER OWSIANEK.

Witnesses:

ARTHUR E. RIDDLE,
W. A. MILLER.
